UNITED STATES PATENT OFFICE.

MARY B. ROSS, OF NEW YORK, N. Y.

ART OF MANTUA-MAKING.

SPECIFICATION forming part of Letters Patent No. 273,160, dated February 27, 1883.

Application filed September 27, 1882. (No model.)

To all whom it may concern:

Be it known that I, MARY BANKER ROSS, of New York, county of New York, State of New York, have invented a new and useful Improvement 5 in the Art of Mantua-Making, which is fully set forth in the following specification and accompanying drawings, in which—

Figure 1 is a front view of my improved anatomical figure-bust; Figs. 2 and 3, side 10 views, and Fig. 4 a back view thereof.

The object of my invention is to enable ladies to obtain an absolutely perfect fitting dress without attendance upon a mantua-maker or being subjected to the annoyance of 15 repeated fittings to the person and numerous alterations before a satisfactory result is reached. I accomplish this by the employment of an anatomical figure-bust which shall be an exact counterpart of the figure of the 20 body of the lady for whom the dress is to be made; and the novelty of my invention is to be found in the application of certain novel rules of measurement, of my discovery, by which such a fac-simile bust may be constructed.

25 To obtain an exact counterfeit of a lady's person from the neck to the hips, I take a block having the general outlines of a female figure, but no larger in any part than the corresponding part of the person to be imitated, and then 30 by pads of any sufficiently firm material build thereon in all its parts, according to the following rules, until it assumes the shape and consisteney which will enable the dress-maker to fit the dress thereupon instead of upon the 35 body of her customer.

By no known rules of measurement heretofore employed can a bust be produced upon which a dress can be satisfactorily fitted.

The bust once correctly obtained, any number 40 of dresses may be produced thereon, of any style which the prevailing fashion demands.

First, measure the lady, a counterfeit of 45 whose bust is to be built, from the collar-bone to the bottom of the waist, which, for the purpose of explanation, may be assumed to be fourteen inches, on the line marked A; second, from the back of the neck to the nipple, on line B, say fourteen inches; third, side of the neck to the tip of the shoulder, on line C, say six 50 inches; place a rule or tape horizontally outward from the side of the neck and drop it two inches; this gives the slant of the shoulder

with unfailing accuracy; fourth, from the collar-bone around the neck, on line D, say fifteen inches; fifth, across the chest two inches 55 below the collar-bone, on line E, say seven inches; sixth, from a point beneath the arm, well back, where the under arm seam of a dress should be, to the center of the bust, across the bosom, on line F, say thirteen inches; seventh, 60 around the waist, on line G, say thirty inches; eighth, from armpit to waist, on line H, say seven inches; ninth, around the hips, on line I, say forty-seven inches; tenth, from back of neck to bottom of waist, on line J, say fifteen 65 inches; eleventh, across the shoulders, on line K, say fourteen inches; twelfth, around the body, over the bosom, on line L, say forty-two inches.

Covering the figure with cloth of any suitable kind and padding the same as necessary to the precise measurements thus obtained will give a shape to which a dress may be fitted with certainty of its absolute conformity to the person of the intended wearer. 70

If care is taken and these directions followed, the result will be a dress which for comfort and capacity of free and easy movement for the limbs can be attained only by the most accomplished artists fitting a dress directly to the 80 person, and never by the employment of the rigid figure-busts heretofore somewhat in vogue.

The human figure is elastic, and, especially in the region of the lungs, provision should be 85 made, as far as possible, for the constant expansion and retraction incident to the proper play of the vital organs. Therefore, for a covering of the block upon which the perfect outline is to be built, I prefer a cloth composed 90 for the most part of wool, because it is quite sure to possess sufficient elasticity, and is, moreover, of a soft, pliant, and clinging nature; or, in other words, it is a material capable of imitating by its constituent properties 95 the feel and springy quality of human flesh more nearly than any other. An article known in the market as "cashmere" is well adapted to these requirements. With such material I envelop the block, leaving openings under 100 the shoulder-blades and near the center of the chest-line in front. This sack or envelope should be in all its parts, except, perhaps, in the back, below the shoulder-blades, slightly

less than the measurements as directed. Pieces of non-elastic tape, an inch or so in width, of precisely the same length as the measurements taken as hereinbefore specified, 5 are then to be secured firmly at their ends to the envelope, in the same positions which the measuring-tape occupied when employed upon the human figure, as indicated in the drawings. By means of a spatula or other thin and flexible instrument, insert at the neck and in the 10 openings left in the envelope or case sufficient curled hair or other elastic fibrous substance to stretch the envelope to the full capacity of the tapes secured thereto, after which the 15 tapes are closed by needle and thread. This will give a figure conforming to the exact proportions, so far as is desired, of the person who is to wear the dress, and possessing the natural and life-like attributes of rigidity and 20 firmness in the back and of soft, pliant, rounded, and elastic plumpness in front which characterize the torso on an elegant female. When, as not infrequently happens, defects 25 of personality are to be concealed or counterfeited charms introduced, the skill of the artist

will find the foregoing provisions for building up the anatomical figure-bust peculiarly adapted to her convenience in the accomplishment of her task, as will readily be understood by those familiar with the art to which 30 my invention relates.

I am aware that anatomical figure-busts have heretofore been constructed to facilitate mantua-making, and therefore make no claim for the use of such a figure-bust, however constructed. 35

What I claim, and desire to secure by Letters Patent, is—

The herein-described improvement of the art of mantua-making, which consists of the 40 following steps, namely: first, taking the hereinbefore-detailed measurements of the person of the intended wearer of the mantua; secondly, shaping an anatomical figure-bust by said measurements; and, thirdly, fitting the 45 mantua to the figure-bust thus obtained.

M. B. ROSS.
